W. F. BACH

HANGER FOR WALL RADIATORS

Filed Dec. 9, 1925

UNITED STATES PATENT OFFICE.

WILLIAM F. BACH, OF CLEVELAND HEIGHTS, OHIO.

HANGER FOR WALL RADIATORS.

Application filed December 9, 1925. Serial No. 74,328.

This invention relates to hangers for wall radiators and has for its principal object the provision of means for strengthening the lower end of the hanger and minimizing lateral movement of the base supporting shoe.

It is also an object to so construct the lower or base supporting portion of a wall radiator hanger, as to prevent deformation of the parts and facilitate assembly.

Other objects will be in part obvious and in part pointed out hereinafter.

In the accompanying drawings forming a part of this application:—

Figure 1 is a side elevation of the hanger;

Figure 2 is a front elevation;

Figure 3 is a section on the line 3—3 of Figure 2; and

Figure 4 is a plan view of the lower foot or flange.

The hanger constructed in accordance with my invention includes supporting body preferably formed of one piece 6 of strap metal of medium weight, having its upper end provided with a slotted plate 7, between which and said upper end is secured an angle-iron bracket 8 mounting a radiator engaging bolt 9. This plate 7 and the bracket 8 are secured to the body 6 by a common means such as rivets.

The lower portion is substantially reverse S-shape, including an upper pair of forwardly projecting parallel arms 10 whose ends are connected by a bar 11, the arms being formed with a pair of vertically aligned bolt holes. The lower end of the body is bent forwardly to form a base supporting foot or flange 13 having a bolt hole 14 aligned with the upper bolt holes 12. This foot 13 is also provided with a vertical slot 15 which opens through the front edge of the foot and into the lower bolt hole 14. What I term a shoe, comprises a barrel 16 and a blade 17 preferably though not necessarily formed of sheet steel or the like, is disposed at the lower end of the hanger and receives the greater portion of the weight. Ordinarily the tendency to twist and move lat-

erally is not successfully resisted but through arranging the barrel 16 in the lower hole 14, extending the blade 17 through the slot 15 preferably in contact with the walls of the latter, and then passing a bolt 18 through the barrel and bolt holes, I entirely overcome the named objections. This bolt 18 has its head 19 engaging the lower end of the barrel below the foot 13, while its upper end extends above the pair of forwardly projecting arms 10 for threaded engagement with a nut 20 or the like which is designed to variably elevate the shoe with respect to the main portion. This nut 20 is held against accidental rotation by means of a notched plate 21.

The lower end of the body of the hanger is provided with a slotted plate 7' to permit attachment to a wall or the like.

From the foregoing it is clear that the structure is such as facilitates assembly and application as well as wide adjustment and further will successfully resist any tendency of the shoe to twist or move laterally under strain of the load supported or for other reasons. The structure set forth has proven highly satisfactory but it is understood that certain changes may be made within the scope of the appended claim.

I claim:

A wall radiator hanger comprising a body attachable to a wall and having a substantially reverse S-shaped lower portion, said portion having vertically aligned bolt holes, the lower arm of said portion projecting forwardly and having a hole with a slot opening through the adjacent front edge of said arm, a shoe having a barrel vertically slidable through the lower hole, a bolt passing through the holes and barrel, means for vertically adjusting the shoe, and a forwardly extending blade carried by the barrel and projecting through said slot.

In testimony whereof, I do affix my signature.

WILLIAM F. BACH.
